Patented Oct. 30, 1917.

2 SHEETS—SHEET 2.

UNITED STATES PATENT OFFICE.

JAMES W. WELLINGTON, OF JACKSON, MICHIGAN.

AUXILIARY CONSTANT-FUEL-SUPPLY APPARATUS FOR AUTOMOBILES.

1,244,667.

Specification of Letters Patent. Patented Oct. 30, 1917.

Application filed November 20, 1915. Serial No. 62,679.

To all whom it may concern:

Be it known that I, JAMES W. WELLINGTON, a citizen of the United States, residing at 802 First St., Jackson, county of Jackson, State of Michigan, have invented certain new and useful Improvements in Auxiliary Constant-Fuel-Supply Apparatus for Automobiles, of which the following is a specification.

10 This invention relates to improvements in an auxiliary constant fuel supply apparatus of an automobile.

The main objects of this invention are:

First, to provide in an electric apparatus 15 of this kind means whereby the supply of fuel to the carburetor is automatically maintained and controlled.

Second, to provide an improved electrical apparatus of this character which is simple, 20 durable and cheap in construction and effective and efficient in operation.

Third, to provide an apparatus which is easily mounted in an automobile and which requires little or no care for the operation 25 and maintenance of the same.

Further objects, and objects relating to details and economies of construction and operation will definitely appear from the detailed description to follow.

30 I accomplish the objects of my invention by the devices and means described in the following specification. The invention is clearly defined and pointed out in the claims.

35 A structure which is a preferred embodiment of my invention is clearly illustrated in the accompanying drawing forming a part of this specification, in which:

Figure I is a dotted side elevation of an 40 automobile showing the location of my auxiliary gasolene tank and its connection to the supply tank in the rear of the car and to the carburetor.

Fig. II is a detail vertical section through 45 the auxiliary supply tank and feed means showing the operating mechanism, all of which constitutes a single unit.

Fig. III is a detail vertical section showing the connection of the float arm to the 50 switch operating arm, taken on a line corresponding to the section line 3-3 of Fig. II.

Fig. IV is a detail vertical section of a 55 modification of my auxiliary supply gasolene tank and feed means wherein the pump

and motor are on a mounting separate from that of the tank and switch.

In the drawing, similar reference characters refer to similar parts throughout the several views, and the sectional views are 60 taken looking in the direction of the little arrows at the ends of the section lines.

1 is an automobile, on the dash of which, preferably within the hood, is mounted my auxiliary gasolene tank 2 which connects by 65 supply pipe 3 to the carburetor 4, the latter being at a lower level than that of tank 2. 5 is the auxiliary tank cover. Pipe 6 extends from main gasolene tank 7, here shown 70 situated in the rear of the car, to a pump connection on the cover. Cover 5 integrally constitutes the motor base 8 and the pump cylinder 9. From one side of cylinder 9 runs the inlet passage 10 which connects to pipe 6. A ball check valve 11 is situated so 75 as to permit the flow of gasolene toward the pump. On the other side of cylinder 9 is the pump discharge passage 12 which delivers to the tank 2 by the ball check valve 13. Within the pump cylinder 9 is the 80 pump plunger 14 reciprocated by an electric motor 15 and its connections. On the base 8 is mounted the electric driving motor 15 which connects by pinion 15' to the pump driving gear 16 secured to the gear shaft 17, 85 the journal bearings of shaft 17 not being shown. On shaft 17 is also mounted the pump eccentric 18. Within the hollow plunger 14 is disposed the pump spring 19 which maintains the plunger in operative 90 contact with the eccentric 18. There is no eccentric ring. The eccentric is a cam.

Within the tank 2 is the float 20 connected by a float arm 21 to one end of float arm rock shaft 22. Where float arm rock shaft 95 22 passes through cover 5 any leakage is prevented by gland 24, the cover being pocketed at this point as shown in Figs. II and III to accommodate the structure.

On cover 5 is mounted the motor switch 10 consisting of the movable arm 25 and the stationary arm 26. Arm 25 is pivoted at 27 and forked at 25' and 25'' so as to permit the actuating arm 23 to play between the fork arms. The switch controls the 10 circuit 28 to the motor 15 from the storage battery 29 of the car or any other source of electric energy. It is evident, therefore, that when the float is at its highest or lowest point the switch will be respectively opened 11

or closed by the action of arm 23, and when closed the motor rotates eccentric 18 which reciprocates plunger 14 thus pumping gasoline from supply tank 7 to auxiliary tank 2, the check valves permitting the flow of gasoline in one direction. The supply of gasoline is then gravity fed from tank 2 to the carburetor and the supply is kept constant by the electric pump means.

A modification of my structure is shown in Fig. IV. The motor and the pump with operating means for the same, are mounted on a base 30 which is separate from the tank cover 31. The pump discharges through discharge pipe 32 to the auxiliary tank, pet cock 36 serving to drain said tank when necessary. The control switch is as usual mounted on the tank cover 31. The movable arm 33 of the switch is actuated by the forked actuating member 34 which is fastened to the rock arm shaft 22, said arm being connected to the ball float 35, as usual. Other parts of this modification are the same as those shown in my preferred structure. It is seen by this, that although the auxiliary tank will have to be mounted at a level higher than that of the carburetor, the pump with its driving mechanism, may be placed in any part of the car, but will always be automatically controlled and operated.

Having thus described my invention, what I claim as new and desire to secure by Letters Patent is:

1. In a constant fuel supply system, the combination of an auxiliary tank, a pump for the filling of said tank, an electric motor for operating said pump, a float

within said tank, a float arm rock shaft journaled in the tank cover, a float arm 40 connecting the float, a switch having a forked movable arm, a switch actuating arm mounted on the float arm rock shaft, said switch actuating arm playing between the forks of said switch arm, whereby the switch 45 is controlled by said float, as specified.

2. In a constant fuel supply system, the combination of an auxiliary tank with a detachable cover therefor, a pump on said cover for filling the same from the main 50 supply, an electric motor for operating said pump, an electric circuit and source of supply, a float within the said tank, connections from said float to control the said circuit all of which are disposed on said cover 55 as a base, coating for the purpose specified.

3. In a constant fuel supply system, the combination of an auxiliary fuel tank provided with a detachable cover having a fuel passage formed therein for discharging 60 fuel into said auxiliary tank, a pump connected with said fuel passage and adapted to force fuel therethrough, means for driving said pump, and means controlled by the level of the fuel in said auxiliary tank 65 for controlling said driving means, said pump driving means and controlling means being mounted upon said cover.

In witness whereof, I have hereunto set my hand and seal in the presence of two 70 witnesses.

JAMES W. WELLINGTON. [L. S.]
